UNITED STATES PATENT OFFICE.

LOUIS L. ANSART, OF NEW YORK, N. Y., ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

Application filed December 8, 1921. Serial No. 520,799.

To all whom it may concern:

Be it known that I, LOUIS L. ANSART, a citizen of the United States, residing in borough of the Bronx, in the county of the Bronx, city and State of New York, have invented certain new and useful Improvements in Combined Typewriting and Computing Machines, of which the following is a specification.

10 This invention relates to combined typewriting and computing machines, settable for addition or subtraction, and, more particularly, to state-controlling means effective during the return or backing movement of the carriage, and is herein illustrated as applied to a bookkeeping machine of the Underwood-Hanson type.

In such machines now in use, the state-controlling for addition or subtraction is effected automatically in the letter-feeding movement of the carriage, but no state-controlling is effected during the return movement thereof. Means have been proposed whereby, when the machine is set for subtraction, upon backing the carriage into a computing zone, the machine will be reset for addition, thus insuring the proper setting of the machine when backed into an addition zone, but failing to insure subtraction-setting upon backing the machine into a subtraction zone. Means have also been proposed whereby the proper setting of the computing mechanism will be insured upon backing into a zone irrespective of the addition or subtraction character of the zone.

The main object of the invention is to provide improved means, simple in construction, economical to manufacture and 40 easily applicable to machines in use, whereby the proper setting of the machine will be insured in case the carriage is backed into either an addition or a subtraction zone.

45 In carrying out the present invention, advantage is taken of the fact that actuation of a motor-trip by the carriage will reset the machine for addition if previously set for subtraction. To this end, the tappet on the motor-trip-lever is provided with a beveled face on the side engaged by an addition-stop as the carriage is backed into the corresponding computing zone, and, in or-

der to facilitate the camming down of the tappet in said return movement, the tappet is so pivoted on the motor-trip-lever and so controlled that it will be turned back sufficiently from its normal position to furnish a camming angle of greater effectiveness.

55 In backing into a subtraction zone, it is obviously undesirable to trip the motor, for, if the machine is set for subtraction, it is undesirable to disturb the mechanism, and, if set for addition, no change in the condition of the computing mechanism will be effected. Consequently, the subtraction-stop or subtraction-state-controller is provided with a hinged downward projection which is supported against yielding when it is brought into engagement with the tappet of the motor-trip-lever during a letter-feed movement of the machine, but which will yield when brought into engagement with this tappet during a backing or return movement of the carriage.

70 In machines of this kind, subtraction-setting during a letter-feeding movement of the carriage into a subtraction zone is effected by a cam-bar carried by the corresponding subtraction-stop and extending substantially the length of a computing zone which, as the carriage enters a computing zone, engages and depresses the tappet on the subtraction-trip-lever and maintains the lever in actuated condition until 85 the carriage passes out of the computing zone. In machines heretofore in use, the tappet has been supported on the subtraction-trip-lever so as to yield when engaged by the cam-bar during a return movement 90 of the carriage. According to the present invention, however, the cam-bar on each stop is utilized to actuate the subtraction-trip-lever in the return movement, as well as in the letter-feed movement of the carriage, and the tappet on the subtraction-trip-lever is modified in form and so supported on the subtraction-trip-lever as to 95 transmit movement from the cam-bar to the subtraction-trip-lever irrespective of the direction of movement of the carriage.

100 For convenience, the tappets on the motor-trip-lever and on the subtraction-trip-lever may be of the same general shape, and supported on the corresponding levers in the same general manner.

In case there is a considerable movement of either of the tappets on the trip-levers when the carriage is backed into a computing zone, the carriage may pass several letter-spaces into the computing zone before the desired trip-lever is actuated. To avoid such lost motion, the pivot of the tappet or dog may be placed sufficiently close to the upper end of the tappet that a small angular movement about the pivot will produce the proper change of camming angle on the left-hand side of the tappet looking from the front of the machine. Preferably the right-hand tapered or cam edge of each 15 tappet is so inclined as to readily co-operate with the corresponding portion of the proper stop mounted on the carriage, and the left-hand tapered edge is at a comparatively steep angle, but so inclined, however, 20 that a slight rocking of the tappet or dog to the right about its pivot will bring the left-hand beveled edge to a proper camming angle.

Hitherto, the general operator has been 25 automatically operated as the carriage passes out of a computing zone, and consequently the machine has been reset for addition, if otherwise set while in the zone, and, upon entering a subtraction zone, the computing 30 mechanism has been automatically set for subtraction. There has, however, been no provision of means to insure an addition setting when the carriage is moved into an addition zone in the letter-feed direction.

In order, however, to prevent improper action of the computing mechanism in an addition zone, due, for example, to the setting of the machine to subtraction manually 40 before it enters the zone, provision is made, according to the present invention, of suitable means to avoid the possibility of such errors. To this end, the ordinary addition-stops are provided with bars extending left- 45 wardly therefrom substantially the length of a computing zone, and these bars are provided with offset portions, in the form of tappets or dogs, which, upon movement of the carriage into addition zones in the letter-feed direction, will actuate the motor-trip and insure the proper setting of the computing mechanism for computing in the addition zone or zones. Obviously, no advantage is gained by actuating the general 55 operator as the carriage backs out of an addition zone, and, to avoid such actuation, the offset portion or dog at the left-hand end of the bar of the addition-stop may be mounted thereon, so as to yield when engaged by the addition-trip-tappet during a backing movement of the carriage.

It will be evident that, according to the present invention, very slight changes in existing machines are necessary to insure 60 proper state-setting of the computing mech-

anism under the control of the carriage in the return movement of the carriage, as well as in the letter-feed movement thereof.

Other features and advantages will hereinafter appear.

In the accompanying drawings,

Figure 1 is a diagrammatic side view, partly in section, showing the invention applied to so much of an Underwood-Hanson machine as is necessary for the purpose of 70 illustration.

Figure 2 is a perspective view showing the form of subtraction-stop utilized in the preferred form of the invention.

Figure 3 is a view showing the position of 80 the subtraction-trip-lever during the passage of the carriage through a computing zone in a letter-feed direction.

Figure 4 is a view similar to Figure 3, but shows the subtraction-trip-lever released and the motor-trip-lever actuated as the carriage passes out of the computing zone.

Figure 5 is a view similar to Figure 3, but shows the position of the parts as the carriage is backed into the computing zone corresponding to the left-hand subtraction-stop shown in Figure 3.

Figure 6 is a fragmentary view showing the actuation of the motor-trip-lever by an 85 addition-stop as the carriage is backed into the corresponding addition zone.

Figure 7 is a view showing the parts in the position assumed after the carriage has entered the computing zone corresponding 100 to the addition-stop, which is shown to the left of the two subtraction-stops. This view shows the preferred form of motor-trip-tappet or dog and the preferred form 105 of addition-stop which insures a proper setting of the computing mechanism when the carriage moves into an addition zone in the letter-feed direction.

Upon movement of a carriage 11 into a computing zone, a frusto-conical roll 12 on 110 a denominational selector 13 will ride up the tapered end of a roller or zone-controller 14, thereby raising a selector dog or tappet 15, mounted on the selector in the usual manner, into position to actuate denominational jacks 16 seriatim as the carriage is fed through the computing zone as a result of the successive actuation of numeral-keys, not shown. The denomination-selector 13 is mounted for swinging movement about a 115 rod 17, extending across the carriage at the rear and carried thereby, and may be set at different positions along said rod by means of a tooth 18 on the selector which may be set in notches arranged at letter-space positions along a second rod 19. Obviously, more than one denomination-selector 13 may be used.

The denominational jacks 16, when operated, act through well-known means, not 120

shown, to advance denominational bars 21 to bring index-pins 22 carried thereby into position beneath the setting bars 23 of numeral-key-actuated linkages. When the carriage is in a letter-space position in the computing zone, a corresponding denominational bar 21 will be in position for setting of the pins 22 thereon, and, upon actuation of a numeral-key, a proper setting bar 23 will be depressed, and a pin 22, of the same value as the numeral-key depressed, will be depressed into set position. After the indexing of the digits of a number has been completed, a general operator 24 may be given a forward-and-rearward reciprocation by means of motor mechanism indicated in general by reference numeral 25. In the forward movement of the general operator, a bar 26 thereon will engage the lower ends of the depressed index-pins and actuate the corresponding denominational bars 21 to rotate the number-wheels of a corresponding register, not shown, in accordance with the index-pins 22 depressed.

To position the carriage 11 in the various computing zones, determined by denominational-selectors 13, provision may be made of tabulating mechanism including a vertically-movable slide or counter-stop 27 which, when lifted by the depression of a tabulator-key, not shown, will be moved into the path of either an addition-stop 28 or a subtraction-stop 29 set on a notched bar 30, mounted on the carriage at its rear, at a letter-space position corresponding to that of a denominational selector 13. The computing zones are determined by the positions of the selectors 13 on the carriage, and the states of the different zones are determined by addition-stops 28 or subtraction-stops 29 positioned in accordance with the positions of the selectors 13. Preferably the machine is provided with more than one counter-stop 27, so that tabulation may be effected to any denominational position desired in a computing zone.

Upon movement of the carriage out of a computing zone in a letter-feed direction, the corresponding tabulator-stop, irrespective of its addition or subtraction character, will engage a tappet or dog 31 carried by a motor-trip-lever 32 and rock the latter about its pivot 33. Such rocking of the lever 32 will be transmitted through a vertical link 34 to a pivoted bail 35 at the lower part of the machine, and shift a link 36, pivoted at one end to one arm of the bail 35, from a position overlying the rear end of a lever 37. The lever 37 will then be swung about its pivot 38 by suitable means, such as a spring, not shown, and the forward end of the lever, which overlies a projection 39 on a vertical slide 40 guided by pins 41 engaging in slots 42 therein, will depress the slide and rock the lever 43, thereby lifting

a pin 44 forming part of the motor-controlling means. Such lifting of the pin 44 will withdraw its lower end from the path of a lug 45, by which the motor mechanism is controlled, and the latter will be thrown into action, the motor mechanism acting through an arm 46 and a yoke 47 of the general operator 24 to actuate the latter. If desired, the slide 40 may be operated manually by means of a finger-piece 48 at the upper end thereof. The motor mechanism and controlling means therefor may be in general the same as that disclosed in the patent to R. F. Hoyt, No. 1,280,228, granted October 1, 1918.

Each subtraction-stop 29 may be provided with means whereby subtraction-setting of the computing mechanism may be controlled. For this purpose, a cam-bar 49 of substantially the same length as the computing zones is attached to the subtraction-stop 29 so as to extend therefrom in the letter-feed direction. As the carriage enters the subtraction zone, the forward end of the cam-bar 49 will engage a tappet or dog 50 carried by a subtraction-trip-lever 51 and rock the latter about its pivot 33 which is the same as that of the motor-trip-lever 32. Such movement of the subtraction-trip-lever 51 will be transmitted by means of a link 52 and a pivoted bail 53, connected thereto, to a latch-member 54 to withdraw the latter from a position underlying the end of a rearwardly-extending arm 55 of a three-armed lever 56 mounted on a shaft 57. The lever 56 will then be turned in a clockwise direction, Figure 1, by a spring 58 attached to the upper end of an upwardly-extending arm 59 of the lever 56. Such movement of the lever 56 will rock the shaft 57 and withdraw to ineffective position a hook 60 fixed on the shaft and normally engaging a notch 61 in a subtraction-bar 62. When released the subtraction-bar will be drawn rearwardly by a spring 63 attached thereto.

A pin 64 on the subtraction-bar 62 extends through a slot in an arm 65 fixed on a rock-shaft 66, and an arm 67 also fixed on the rock-shaft 66 is provided at its free end with a slot through which extends a pin 68 at the rear end of an arm 69 fixed on a plate 70 pivoted at its upper edge. The lower edge of the plate 70 projects into notches in shafts 71 of the key-actuated pin-setting mechanism, and, upon rearward movement of the subtraction-bar, the shafts 71 will be moved forwardly to change the connections between the same and the pin-setting bars 23, so that the pins set on the pin-bars or denominational bars 21 will not be those corresponding in value to the numeral-keys depressed, but will correspond in value to the complements, to the base nine, of the numeral-keys depressed. Subsequent actuation of the general operator 24 will

effect subtraction by the well-known complementary method.

Upon the advance movement of the general operator 24, which will occur as the carriage 11 passes out of each computing zone in a letter-feed direction, bar 26 will engage a cam-surface on a forwardly-extending arm 72 of the three-armed lever 56, and turn the latter in a clockwise direction 10 against the action of the spring 58, so that the hook 60 may again engage in the notch 61 of the subtraction-bar 62, which is also restored to normal position by engagement of the bar 26 of the general operator with 15 a lug 73 on the subtraction-bar. As soon as the lever 56 is restored to its normal position, the latch-member 54, which has been released from the control of the cam-bar 49 of the subtraction-stop 29 which has 20 just moved out of the computing zone, will move under the rear end of the arm 55 of said lever 56 and the subtraction-bar 62 will be locked in its ineffective position.

In the application of H. H. Vickers, 25 Serial No. 451,120, filed March 10, 1921, (now Patent No. 1,456,660, dated May 29, 1923) the tappet on the motor-trip-lever is beveled on both sides, so as to be actuated in either direction, and the movement of the 30 tappet about its pivot, when engaged by a stop moving in a return direction is limited so as to render the tappet effective during such movement, and, at the same time, to enable a decrease of the camming 35 angle of the left-hand inclined face of the tappet, so as to facilitate the actuation of the motor-trip-lever. In other words, the camming angle of the left-hand edge of the tappet is too great when in normal position, but, upon a slight turning to the right to its limiting position, the camming angle is decreased to such an extent that the tappet and the supporting lever may be shifted 40 by the stop without difficulty.

45 In the preferred form of the present invention, the tappet is similar in form to that disclosed in the Vickers application, and similarly mounted on its supporting lever. The motor-trip-lever 32 comprises a 50 main portion 74 and a parallel portion 75, which extends from the end of the lever farthest removed from the link towards said link far enough to receive the pivot 33, the portions 74 and 75 being spaced at 55 the proper distance apart by suitable means. The tappet 31 is positioned between the two portions of the motor-trip-lever and held therein by means of a pivot 76 extending through the tappet 31 and supported in 60 the lever on opposite sides of the tappet. An adjusting screw 76^a, threaded into the left-hand end of the lever 32, as shown in Figures 3 to 7, inclusive, furnishes a left-hand abutment for the tappet against which 65 the tappet is held by means of a suitable

spring 77, the movement of the tappet 31 in the opposite direction being limited by means of a pin 78.

The right-hand camming face 79 of the tappet 31 presents such a camming angle 70 to the stops in a letter-feeding movement of the carriage that the stops and tappet will readily co-operate to rock the motor-trip-lever 32. In the normal position of the tappet 31, however, the left-hand camming face 75 80 is in too steep a position for the tappet to be readily cammed down by a tabulator-stop, but, upon engagement by the stop during a return movement of the carriage, the tappet 31 will be tilted from the position shown in Figure 5 to that shown in Figure 6, and the camming angle decreased sufficiently to enable ready actuation of the motor-trip-lever 32. The structure just described is in general similar to that in the Vickers application, but the pivot 76 is placed somewhat higher, so that, for a given angular movement of the tappet 31, the effective camming angle of the face 85 90 95 100 105 110 115 120 125 130 135 140 145 150 155 160 165 170 175 180 185 190 195 200 205 210 215 220 225 230 235 240 245 250 255 260 265 270 275 280 285 290 295 300 - erator will be the complements, to the base nine, of the digits typed, and, upon actuation of the general operator, subtraction by the complemental method will be effected.
- 5 Upon movement of the carriage in the opposite direction into the computing zone, the addition-stop 28 in a position corresponding to the zone will actuate the motor-trip-lever and thereby cause actuation of the general operator and a consequent re-setting of the machine for addition, if it were previously set for subtraction. As previously pointed out, the cam-bar 49 will actuate the subtraction-trip-lever when the carriage is backed into the corresponding computing zone, and, if the subtraction-stop were formed in the usual manner, it would actuate the motor-trip-lever which might interfere with the setting for subtraction or even reset for addition.
- At best, such actuation of the motor-trip-lever would be undesirable. To avoid this difficulty, provision may be made whereby each subtraction-stop will be ineffective on the motor-trip-lever during the return movement of the carriage into the corresponding computing zone. As shown in Figure 2, the preferred form of subtraction-stop is formed of a left-hand side plate 83 and a right-hand side plate 84 adapted to fit over the toothed bar 30 and to enter notches between the teeth 85 on the lower side of the bar, so as to include three of said teeth, the plates 83 and 84 being held in proper position apart by a spacer 86 near the front part thereof and spacers 87 at the rear, the usual cam-bar 49 having a portion extending upwardly inside of the side plate 83 and secured to the stop. To render the subtraction-stop ineffective on the motor-trip-lever when moving in a return direction, provision is made of a pawl or dog 88 mounted on a pivot 89 carried by a block 90 secured to the right-hand side plate 84 in any suitable manner, and the pawl 88 is prevented from yielding when engaged by the motor-trip-tappet during a letter-feed movement of the carriage by means of a bar 91 extending across the slot in the plate 84 in which the pawl 88 is mounted, and the pawl 88 is normally urged to this limiting position by a spring 92 secured to the side plate 84 and engaging a portion of the pawl 88 above its pivot 89.
- 55 In Figure 5, the pawl 88 is shown as swung to an ineffective position, when engaged by the pawl or tappet on the motor-trip-lever 32, so as to prevent actuation of the motor-trip-lever; and Figure 6 shows the actuation of the motor-trip-lever as the carriage is backed into the computing zone corresponding to the addition-stop. Figure 7 shows the position of the various parts after the carriage 11 has been backed into the computing zone corresponding to the
- addition-stop or state-controller shown to the left of the subtraction-stops.
- In the preferred form of the tappet 31, which is shown best in Figure 7, the right-hand cam-face 79 is at the proper camming angle to enable actuation thereof by one of the stops 28 or 29 during the letter-feed movement of the carriage, the left-hand cam-face 80 lying at a comparatively steep angle, so as not to interfere with the release of the tappet by the dog when passed by the latter in the letter-feed direction. Upon movement of the carriage in the return direction, however, the tappet will, upon engagement of the tappet 31 by an addition-stop, be swung to the right sufficiently to bring its left-hand face 80 to the proper camming angle, and, as the distance of the point of the tappet from the pivot 76 is comparatively short, the proper change of angle of the inclined face or edge 80 will be effected in connection with a very small angular movement of the tappet 31, so that the difference in position of the point of the tappet, when cammed down by an addition-stop moving in the letter-feeding direction or moving in the return direction, will be very slight, and consequently the so-called lost motion will be reduced to a great extent.
- The mechanism so far described provides means to insure a proper setting of the computing mechanism when the carriage enters a computing zone, except when the carriage enters an addition zone in the letter-feed direction. To insure proper setting of the computing mechanism, for this condition, provision may be made of means for tripping the motor as the carriage is moved in a letter-feed direction into the addition zone, thereby insuring the proper setting, since, if the machine were previously set for subtraction, the actuation of the general operator would result in a resetting for addition. To this end, each addition-stop 28 may be provided with a bar 93 extending to the left therefrom, and with a hinged tappet or dog 94 extending substantially at right angles thereto and held against a stop 95 on the bar 93 by means of a spring 96, so that the tappet 94, when it engages the tappet 31 during the letter-feed movement of the carriage, will actuate the motor-trip-mechanism, and, upon engagement of the tappet 31 by the tappet or dog 94 during a return movement of the carriage, the dog 94 will yield and pass the tappet 31 without actuating the same.
- It will be seen that, according to the present invention, the proper setting of the computing mechanism in either an addition or a subtraction zone is insured, irrespective of the direction of movement of the carriage in entering any of the zones.
- Variations may be resorted to within the

scope of the invention, and portions of the improvements may be used without others.

Having thus described my invention, I claim:

5. 1. In a combined typewriting and computing machine, in combination, a carriage, computing mechanism normally set for addition, and including means for indexing numbers and a general operator for effecting 10 computation of numbers so indexed and means, including a controlling device settable at letter-space intervals along the carriage, for setting said computing mechanism for subtraction irrespective of the 15 direction of movement of the carriage.
2. In a combined typewriting and computing machine, in combination, a carriage, computing mechanism normally set for addition, and including means for indexing 20 numbers and a general operator for effecting computation of numbers so indexed carriage-controlled means for determining computing zones, and means, including a controlling device settable at letter-space 25 intervals along the carriage, for setting said computing mechanism for subtraction upon entering a computing zone in either direction.
3. In a combined typewriting and computing machine, in combination, a carriage, computing mechanism normally set for addition, and including means for indexing numbers and a general operator for effecting computation of numbers so indexed, carriage-controlled means for determining computing zones, and means, including a controlling device settable at letter-space 35 intervals along the carriage, effective for setting said computing mechanism for subtraction upon entering a subtraction zone in either direction, and effective to reset 40 said computing mechanism for addition when the carriage passes out of the subtraction zone in a letter-feed direction, but 45 ineffective for such resetting when the carriage is backed into the subtraction zone.
4. In a combined typewriting and computing machine, the combination, a carriage, carriage-controlled means for determining 50 computing zones, a motor-trip lever, a tappet supported on said motor-trip lever, so as to be actuatable during movement of the carriage in either direction, a subtraction-trip lever, a tappet supported on said subtraction-trip lever, so as to be actuatable during 55 movement of the carriage in either direction, a motor-trip actuator effective when properly positioned on said carriage to engage the motor-trip tappet as the carriage 60 moves out of an addition zone in a letter-feed direction, but ineffective on the subtraction-trip lever, and a subtraction-trip actuator effective, when properly positioned on the carriage, to actuate the subtraction-trip tappet when the carriage enters a subtraction

zone in either direction, said subtraction-trip actuator being provided with a device effective when the carriage is moved out of the subtraction zone in a letter-feed direction to actuate the motor-trip tappet, 70 and yieldable on said subtraction-trip actuator so that in the return movement of the carriage into the subtraction zone, it will yield and be ineffective on the motor-trip tappet. 75

5. In a combined typewriting and computing machine, in combination, a carriage, computing mechanism including a general operator, motor mechanism for actuating said general operator, a motor-trip device 80 to throw said motor mechanism into operation, a subtraction-trip device to set the computing mechanism for subtraction, and a controlling device settable at letter-space intervals along said carriage to actuate said subtraction-trip device irrespective of the direction of the movement of the carriage, and to actuate the motor-trip device only when the carriage moves in the letter-feed 85 direction. 90

6. In a combined typewriting and computing machine, in combination, computing mechanism normally set for addition and including means for indexing numbers and a general operator for effecting computation of numbers so indexed, a carriage, carriage-controlled means for determining computing zones, means, including a subtraction-controlling device settable at letter-space intervals along the carriage, for setting said computing mechanism for subtraction upon movement of the carriage into a subtraction zone in either direction, an addition-controlling device settable at letter-space intervals along the carriage to correspond to an addition zone, and means for re-setting the computing mechanism for addition actuatable by said addition-controlling device upon entering the addition zone in either direction. 100 110

7. In a combined typewriting and computing machine, in combination, a carriage, computing mechanism normally set for addition and including means for indexing numbers and a general operator for effecting computation of numbers so indexed, carriage-controlled means for determining computing zones, subtraction-setting means, means for re-setting the computing mechanism for addition, and a controlling device positioned on the carriage in accordance with an addition zone, to actuate said re-setting means upon movement of the carriage into the addition zone in either direction. 115 120

8. In a combined typewriting and computing machine, in combination, a carriage, computing mechanism normally set for addition, carriage-controlled means for determining computing zones, subtraction-setting 130

- mean, means for re-setting the computing mechanism for addition, and a controlling device positioned on the carriage in accordance with an addition zone, adapted to actuate the re-setting means when the carriage is moved out of the addition zone in a letter-feed direction or is backed into said zone, and effective to actuate said re-setting means when the carriage enters the addition zone 10 in the letter-feed direction, but ineffective when the carriage is backed out of the zone.
9. In a combined typewriting and computing machine, in combination, a carriage, carriage-controlled means for determining computing zones, a motor-trip lever, a tappet supported on said motor-trip lever, so as to be actuatable during movement of the carriage in either direction, a subtraction-trip lever, a tappet supported on said subtraction-trip lever, so as to be actuatable during movement of the carriage in either direction, a motor-trip actuator effective when properly positioned on said carriage to engage the motor-trip tappet as the carriage moves into or out 20 of an addition zone in a letter-feed direction, but ineffective on the subtraction-trip lever, and a subtraction-trip actuator effective when properly positioned on the carriage to actuate the subtraction-trip tappet when the carriage enters the corresponding subtraction zone in either direction, said subtraction-trip actuator being effective to actuate the motor-trip tappet when the carriage moves out of the subtraction zone in 30 35 a letter-feed direction, but ineffective during the backing of the carriage through the subtraction zone and during entrance of the carriage into the subtraction zone in the letter-feed direction.
- 40 10. In combination, a traveling carriage, computing mechanism normally set for addition and including means for indexing numbers and a general operator for effecting computation of numbers so indexed, carriage-actuated means for determining computing zones, subtraction-setting means, and means, actuatable by backing the carriage into a subtraction zone, to set the machine for subtraction, if set for addition.
- 50 11. In combination, a traveling carriage, computing mechanism normally set for addition and including means for indexing numbers and a general operator for effecting computation of numbers so indexed, carriage-actuated means for determining computing zones, subtraction-setting mechanism returnable to ineffective position by the general operator, and means for automatically causing actuation of the general operator upon movement of the carriage into an addition zone in a letter-feed direction.
- 55 12. In combination, a traveling carriage, computing mechanism normally set for addition and including means for indexing numbers and a general operator for effecting computation of numbers so indexed, 60 65
- ing computation of the numbers so indexed, carriage-actuated means for determining computing zones, subtraction-setting mechanism returnable to ineffective position by the general operator, and means effective for automatically actuating the general operator upon backing of the carriage into an addition zone, but ineffective for actuating the general operator when backing into a subtraction zone. 75
13. In combination, a traveling carriage, computing mechanism normally set for addition and including means for indexing numbers and a general operator for effecting computation of the numbers so indexed, carriage-actuated means for determining computing zones, subtraction-setting means returnable to ineffective position by the general operator, and automatic means for insuring the proper setting of the computing mechanism upon entrance of the carriage into an addition zone or a subtraction zone irrespective of the direction of movement of the carriage. 80 85
14. An addition state-controller to be set on the carriage of a combined typewriting and computing machine in accordance with the computing zone determined by the latter, said machine having mechanism for indexing numbers digit by digit, a general operator for effecting computation of numbers so indexed, subtraction-setting means actuatable by the carriage and resettable by the general operator, and carriage-controlled motor mechanism for actuating the general operator, said addition state-controller comprising a body-portion settable on a rack bar on the rear of the carriage in accordance with the position of an addition zone, and provided with a portion to actuate the motor mechanism irrespective of the direction of movement of the carriage, an extension, of substantially the length of the addition zone, attached to said body-portion, and a dog mounted on said extension at its end, so as to 90 95 100 105 110 115
- actuate the motor mechanism when the carriage enters the addition zone in the letter-feed direction, and to yield and to move to ineffective position when the carriage is backed out of the addition zone. 120 125
15. A subtraction state-controller to be set on the carriage of a combined typewriting and computing machine in accordance with the computing zone determined by the latter, said machine having mechanism for indexing numbers digit by digit, a general operator for effecting computation of numbers so indexed, subtraction-setting means actuatable by the carriage irrespective of the direction of movement of the carriage and resettable by the general operator, and general-operator-actuating motor mechanism actuatable by the carriage irrespective of the direction of movement of the latter, said subtraction state-controller comprising a body-portion 130

settable on a rack bar on the rear of the carriage in accordance with the position of a subtraction zone, and provided with a motor-mechanism-actuating dog mounted on said body-portion, so as to be effective during the movement of the carriage in the letter-feed direction, but to be swung to ineffective position during movement of the carriage in the opposite direction, and an extension, of substantially the length of the computing zone, to actuate the subtraction-setting means, said extension being effective as long as the carriage is in the subtraction zone.

16. A set of state-controllers adapted to be supported in letter-space positions along the carriage of a combined typewriting and computing machine, comprising a subtraction state-controller having a portion to actuate a trip to set the machine for subtraction when the carriage passes into a corresponding zone in either direction, and a dog yieldable to ineffective position when the car-

riage is backed into the subtraction zone, but effective upon movement of the carriage out of the zone in the letter-feed direction to actuate a motor-trip to cause actuation of a general operator and the consequent resetting of the machine to the state of addition, and an addition state-controller having a fixed portion to actuate the motor-trip as the carriage passes out of a corresponding zone in the letter-feed direction, or is backed into the same, and a dog spaced at the width of the zone from the fixed portion yieldable to ineffective position when engaged by the motor-trip during a backing movement of the carriage, but effective in the letter-feed movement of the carriage into the zone to actuate the motor-trip.
